land, Ohio, a corporation of Delaware

Original application May 31, 1938, Serial No.
210,897, now Patent No. 2,265,229, dated Decem-
ber 9, 1941. Divided and this application May
31, 1943, Serial No. 489,112

4 Claims. (Cl. 197—124)

1

This application is a division of my copending application, Serial No. 416,547, filed October 25, 1941, which was, in turn, a division of my then copending application, Serial No. 210,897, filed May 31, 1938, and now issued as United States Letters Patent No. 2,265,229, patented December 9, 1941. The aforesaid application Serial No. 416,547 is directed to the plate clamping means shown herein, while Patent No. 2,265,229 is directed to the combination of a perforating mechanism and the embossing means herein shown.

The present invention relates to preparing printing devices and the like, and particularly to embossing machines for forming type characters on printing devices as on plates or like elements of such devices.

In such embossing machines, the printing plates which are to be embossed are supported in the desired relation to an embossing position while embossing dies are actuated to form the desired type character on the printing plate, and to attain the required distribution of the successively formed characters upon the printing plate, the printing plate is shifted through character spacing, back spacing or like spacing movements with relation to the embossing position of the machine. Such spacing movements are attained through the use of a shiftable carriage means upon which the printing plate is supported, and to improve and simplify such carriage means and its operation through such required shifting or spacing movements is the primary object of this invention.

Further and more specific objects of the invention are to enable the carriage means in such an embossing machine to be indexed or spaced in either direction longitudinally of a line of type coordinate the line spacing and carriage return means so as to simplify the operation of the embossing machine; and to afford a common actuating means for effecting line spacing and carriage return movements.

Other and further objects of the present invention will be apparent from the following description and claims and will be understood by reference to the accompanying drawings which, by way of illustration, show a preferred embodiment and the principle thereof and what I now consider to be the best mode in which I have contemplated applying that principle. Other embodiments of the invention embodying the same or equivalent principle may be used and structural changes may be made as desired by those skilled in the art without departing from the

2

present invention and the purview of the appended claims.

In the drawings:

Fig. 1 is a fragmentary front elevational view of an embossing machine embodying the present invention;

Fig. 2 is an elevational view of a printing plate of the character produced by a machine as illustrated in Fig. 1;

Fig. 3 is an elevational view of a printing and control device in which such a printing plate may be used;

Fig. 4 is a fragmentary plan view of the carriage illustrated in Fig. 1, with the gripping jaws removed therefrom;

Fig. 5 is a horizontal sectional view taken in the direction of the arrows on the line 5—5 on Fig. 4;

Fig. 6 is a fragmentary detail view of a ratchet employed in the arrangement illustrated in detail in Fig. 5;

Fig. 7 is a sectional detail view taken substantially on the line 7—7 on Fig. 6;

Fig. 8 is a front elevational view of the carriage arrangement;

Fig. 9 is a view partly in elevation and partly in section of a portion of the carriage arrangement shown in Fig. 8; and

Fig. 10 is a sectional view taken substantially on the line 10—10 on Fig. 9.

An embossing machine embodying the present invention is illustrated generally in Fig. 1, while a printing plate of the character which such a machine is adapted to produce is shown in Fig. 2.

This printing plate, designated 42, is provided with printing characters which are formed thereon by the embossing machine, such printing characters appearing in relief on one face of the plate 42 and in intaglio on the opposite face of this plate. These characters may be arranged in individual lines as shown in Fig. 2, for example, to enable printing of the various lines of a name 55 and address 56 and supplemental data as 57.

Printing plates such as 42, Fig. 2, are adapted to be mounted on printing and control devices as 40 shown in Fig. 3. As commonly constructed such printing and control devices as 40 comprise a frame 41 having along its lower edge a bead 43 against which the lower edge of the printing plate 42 is fitted. Retaining devices 44 struck from the frame 41 are disposed in spaced relation to the bead 43 and cooperate therewith to retain the printing plate 42 on the lower half of the frame 41, the devices 44 engaging the upper or serpentine edge of the plate 42. To restrain the plate

42 against endwise movement relative to the frame 41, the frame 41 is provided with yieldable tongues 45 disposed at opposite ends of the plate 42 and having projections which seat in notches 47, Fig. 2, formed in the adjacent ends of the plate 42. When it is desired to remove the plate 42 from the frame 41, either of the tongues 45 may be depressed to enable the plate 42 to be slid endwise from the frame.

A bead 50 is formed along the upper edge of the frame 41 and cooperates with retaining devices 51 struck from the frame 41 to removably secure separate index and control cards 52 and 53 in position on the upper half of the frame. The index card 52 has an impression thereon of the data represented by the printing characters constituting the name 55 and address 56 embossed on the printing plate 42, thereby affording a convenient visible indication of such data. The control card 53 and the underlying portion of the frame 41 are adapted to be perforated as shown in Fig. 3 to represent, according to a predetermined code, for example, supplemental data such as the numerical amount printed from the characters 57.

It will be understood, that while I have described the printing plate 42, Fig. 2, as being incorporated in a printing and control device as 40, Fig. 3, this is merely illustrative of the manner in which such a printing plate may be utilized for, as is well understood by those skilled in the art, printing plates such as 42 may be equally well employed in printing devices which are not equipped with control areas such as 53, Fig. 3. In fact, insofar as the present invention is concerned, the use to which a printing plate such as 42 may be put is immaterial and has been described hereinabove only as a matter of general interest.

The embossing machine is so arranged that the die heads 65 and 66, Fig. 1, may be rotated on a vertical axis to bring any selected pair of complementary dies 65a and 66a, Fig. 1, into operative relation with a blank plate 42 carried along the forward side of the machine frame by a carriage 75. The die heads 65 and 66, as herein shown, are fixed in vertically spaced relation on a rotatable vertical shaft 76, Fig. 1, journaled at its lower end in the machine frame 68 and at its upper end in an upstanding arch-like frame element 77. The pairs of complementary dies 65a and 66a are mounted in opposed vertically shiftable relation about the periphery of the die heads 65 and 66 so that any pair, selected and shifted by rotation of the die heads to an embossing position at the forward side of the machine, may be brought together to emboss the selected character on the plate 42 positioned between the selected pair of dies.

Actuation of the selected pair of dies 65a and 66a is preferably effected by means which drive the two dies toward each other so as to engage the plate 42 and form the desired character therein without vertically shifting the plate from the full-line position of Fig. 10. In the form illustrated this means, for the upper die 65a, comprises an upper rocker arm 78, Fig. 1, pivoted at 79 on the frame element 77 and operated by a toggle 80, interposed between said arm 78 and an actuating shaft 81 mounted adjacent to the top of the frame element 77.

The lower die 66a is actuated by a lower rocker arm 85 which has one end pivoted at 85' to the frame 77, while a pitman 86 operated by a crank 87 on a horizontal operating shaft 88 is connect-

ed to its other end. A lower die stock 89, Fig. 7, is mounted for sliding movement in the frame between the lower rocker arm 85, Fig. 4, and the lower die 66a located in embossing position. A similar upper die stock 91, Fig. 1, is provided between the upper rocker arm 78 and the upper die 65a, the die stock 91 being supported for vertical movement on a carrier arm 92 pivoted at 79.

When the shaft 88 is rotating, the two rocker arms 78 and 85 are constantly actuated in unison by the pitman 86 and an operating connection between said shaft 88 and the toggle shaft 81, such operating connection being located at the back of the machine and being shown in detail in the patent to Joseph S. Duncan and Henry E. Hubbard, No. 1,831,103.

As described in the patent to Joseph S. Duncan, No. 1,518,904, the rocking movement of the arms 78 and 85 is normally ineffective to actuate the dies 65a and 66a. To this end shiftable die shuttles 91a and 92a, Fig. 1, are mounted for movement into the path of the arms 78 and 85 only when an embossing operation is desired. The shuttles 91a and 92a are connected by links to opposite ends of a lever 93, which is rocked by means of a bell crank lever 94. This bell crank lever 94 is associated with the die selecting mechanism in the manner disclosed in said Patent No. 1,518,904 so as to render said rocker arms 78 and 85 operable only after selection and proper positioning of a pair of dies.

The selection of the desired pair of dies 65a and 66a is, in the present embodiment, effected by the keys 67a and 67b, Fig. 1, the die-carrying shaft 76 being normally rotated at a high rate of speed and being stopped in any selected position by suitable stop or abutment means operated by said keys. The mechanism for effecting such selective positioning of the die heads forms no part of the present invention, and therefore it will suffice to point out that its specific structure is described in the aforementioned Duncan et al. Patent, No. 1,831,103. It may be stated, however, that as disclosed in said patent, the die-actuating rocker arms 78 and 85 are rendered effective automatically during one rocking cycle of these arms immediately after and as an incident to the stopping of the die heads in any selected position.

The carriage 75, Fig. 1, upon which the plate 42 is supported during the performance of the embossing operations, is so constructed and related to the die-actuating mechanism as to effect automatic step-by-step or character spacing movement, as well as providing for tabulating and back spacing movement and manually effected line spacing of the plate 42. To this end the carriage 75 has its main body portion mounted by means of a plurality of guide rollers 95,

Figs. 8 and 10, on a transverse rail or track 96 which extends across the front of the frame 77. The rollers 95 are so related to the track 96 as to permit movement of the carriage across the front of the machine during, for example, character spacing movement of the carriage, while on the top of the carriage a cross slide 98, Figs. 8 and 10, is provided for movement transversely with respect to the track 96, or toward and away from the die heads. Thus, the cross slide 98 provides for line spacing movement, the plate 42 being supported on the cross slide 98 by releasable clamping means such as the clamping jaws 99, Fig. 10.

As shown in Figs. 8 and 10, the jaws 99 are carried on a mounting member 100 which is de-

tachably secured to the cross-slide 98 by means described hereinafter, the member 100 having upstanding bearing lugs 101 thereon in which a jaw-supporting shaft 102 is journaled. The two jaws 99' and 99'', Fig. 10, are in the nature of opposed plates, the lower one 99' of which carries lugs 103, Fig. 8, through which the shaft 102 rotatably extends, and the upper jaw 99'' has a pivotal connection with the lower jaw 99' by means of pins 104 extending loosely through the two plates 99' and 99''. These pins 104 have securing wires 105 extending therethrough on the outer sides of the two plates, 99' and 99'' and the pins 104 and these plates are so fitted as to permit slight pivotal movement for clamping and unclamping of a printing plate 42.

To provide for clamping of the jaws 99, the plates 99' and 99'' extend at their rear ends so as to embrace opposite sides of the shaft 102, and the shaft is flattened on opposite sides thereof as shown in Fig. 10. Thus when the shaft 102 is rotated in one direction nearly 90° relative to the plates 99' and 99'' and into a position like that shown in Fig. 10, the adjacent rear edges of the plates are separated so as to clamp the forward or outer edges of the plates or jaws upon the printing plate 42. It will be seen in Fig. 10 that a substantially U-shaped spring 106 is provided adjacent the central pin 104 and between the plates 99' and 99'' to separate said plates or jaws to the maximum extent. Preferably the forward end of the upper jaw 99'' is hooked and cooperates in pincers fashion with a flat portion or ledge on the forward end of the lower jaw 99' to firmly clamp the printing plate 42 in position, as shown in Fig. 10. To facilitate accurate positioning of the printing plates between the jaws, a shoulder 107 is formed on the lower jaw 99' slightly inwardly of the flat part thereof, thereby affording a stop for limiting insertion of a printing plate as 42 between the jaws.

In the operation of the jaws 99 to clamp a printing plate 42, the jaws are first rocked toward the operator so as to rest against a loading abutment 110 formed on the member 100. Such movement of the jaws is effected by the shaft 102 which has a 90° rotative lost motion connection with the lower jaw 99', sufficient to enable the shaft 102 to accomplish its jaw-clamping function in addition to its function in moving the jaws between loading and working positions. The desired lost motion is attained by means that are shown and described in my aforesaid Patent No. 2,265,229. To facilitate the operation of the jaws 99, the shaft 102 has a knurled operating disk or knob 111 on its projecting left end, Fig. 8. When the jaws 99 have been shifted to their upright or loading position the shaft 102 is turned to the full extent permitted by its lost-motion connection so as to thereby present the flattened surfaces thereon to the jaws 99' and 99'' and thereby enable the spring 106 to separate the plate-clamping portions of the jaws so as to fully release or unclamp the jaws. The printing plate 42 is then inserted between the jaws 99 which grip the plate sufficiently firmly to enable the jaws to be rotated back to their horizontal position shown in Fig. 10 without releasing the plate, so as to thereby enable the plate to be carried to its working position. This movement of the jaws is limited by an abutment pin 112 Fig. 10, on the cross slide 98, and to securely clamp the printing plate, the operator continues the turning of the shaft 102 to the full extent permitted by its lost motion connection which results in retracting

the flattened portions of the shaft 102 from the jaws 99' and 99'' so as to dispose these portions in the position shown in Fig. 10 and since the rounded portions on the shaft then engage the jaws they are forced into tight engagement with the plate. It will be understood that such rocking movement of the jaws 99 to and from the loading position takes place in the normal use of the machine while the carriage 75 is located at one side of the embossing position.

As herein shown the mounting member 100, Figs. 8 and 10, is secured on the cross slide 98 by means which provides for adjustment of the mounting member parallel to the path of the carriage, and also which provides for adjustment of the mounting member so that the plate 42 carried thereby is positioned with its axis parallel to said path of the carriage 75. To this end the top face of the cross slide 98 has aligned slots 113 and 113', Fig. 4, formed therein generally parallel to the carriage path, and a fixed depending pin 114, Figs. 4 and 8, projects from the mounting member 100 into the slot 113. For co-operation with the other slot 113' a pin 114' is provided which is fixed eccentrically on a small disk 115 mounted in the bottom of the member 100. By means of a stub shaft 115' Figs. 4 and 8 projecting upwardly through the member 100, the eccentric pin 114' may be shifted so as to adjust the mounting member into the desired parallel relation to the carriage path, and by a lock nut 115'', Fig. 8, threaded onto the stub shaft 115', this adjustment may be maintained.

A headed screw 100', Fig. 10, extends through an aperture 100'' in the member 100 and is threaded into the cross slide 98 to secure the mounting member 100 onto the cross slide 98 and, as shown in Fig. 10, the aperture 100'' is somewhat larger than the screw 100' so as to permit the desired horizontal adjustment of the member 100.

To afford longitudinal adjustment of the mounting member 100, a transverse slot 98', Fig. 4, is formed in the cross slide 98 and a headed screw 98'', projecting from the left end of the member 100, Fig. 8, has the lower edge of its head positioned in the slot 98'. Thus, by adjustment of the screw 98'' the positioning of the mounting member longitudinally of the direction of movement of the carriage 75 is determined.

For the purpose of imparting the desired line spacing movement to the printing plates, the cross slide 98 is normally urged to a retracted position by springs 75', Fig. 10, and is advanced line by line by means of a ratchet mechanism 116, Figs. 4 and 5. In the form shown, the cross slide 98 is partially supported and guided on the carriage 75 by a rod 117, Figs. 9 and 10, which is secured to the carriage 75 and is slidably fitted in bearing apertures 118 in depending flanges 119 along the front and rear edges of the cross slide 98.

A rotatable shaft 120, Figs. 5 and 10, is mounted transversely of the carriage 75, and pinions 121 fixed on this shaft mesh with racks 122 formed on depending flanges at opposite ends of the cross slide 98. The shaft 120 carries a ratchet wheel 125, Fig. 5, at one end thereof, and this ratchet is fixed in a rotatively adjustable relation to the shaft 120 through the medium of a non-rotatable collar 126 and two adjusting screws 127, as shown in Figs. 6 and 7 of the drawings. An actuating pawl 130, Figs. 4, 5 and 8, and a control pawl 131 are associated with the ratchet wheel 125 to actuate the shaft 120. As shown in Fig. 5, the ac-

tuating pawl 130 is of an inverted U-form and is pivoted intermediate its ends, at 132, on one end of a carrier arm 133. The pawl 130 has a tooth 134 at one end thereof and this tooth is urged into operative engagement with the teeth of the ratchet wheel 125 by a spring 135 extended between the pawl 130 and its carrier arm 133. The carrier arm 133 is pivotally mounted on the shaft 120 for rotative movement relative to said shaft, so that by rocking said arm from the position of Fig. 5 in a counterclockwise direction the cross slide 98 may be advanced. The carrier arm 133 is normally urged by a spring 134' to its normal position as shown in Fig. 5.

A bell crank 135, Fig. 4, pivoted on the carriage 75 has an actuating arm 135' which engages the downwardly extending end of the carrier arm 133, as shown in Fig. 5, and this bell crank 135 is operated by a second bell crank 136 which is pivoted on the same axis as bell crank 135. One arm of the bell crank 136 extends outwardly from the carriage 75 and constitutes a line space lever 136', Fig. 4, while the other arm has a return spring 137 connected thereto and has a stop shoulder 137' formed thereon which cooperates with an abutment 140' on the carriage 75 to determine the initial position of the line space lever 136'. An operating connection between the line space lever 136' and the transmitting bell crank 135 is provided by a downturned lug 138 on the bell crank lever 136' which overlies the bell crank 135 so that actuation of the lever 136' serves to impart operating movement to the arm 135' of bell crank 135 for thereby actuating the pawl 130. The extent of movement of the lever 136' is limited by abutment faces 140, Fig. 4, on the pawls 135 and 136 which engage the abutment 140' on the carriage 75 so that a full stroke of said lever advances the cross slide 98 one line-space. Having been given such a line spacing movement the cross slide is retained in its advanced position by the control pawl 131, Fig. 5, which is pivoted on the carriage beneath the shaft 120 on a pivot pin 141 and has a tooth 142 operable to engage the ratchet wheel 125. The tooth 142 and the teeth of the ratchet wheel are so related that the yielding force of the springs 75', Fig. 10, tending to produce return movement of the ratchet wheel 125 acts to hold the cooperating teeth in their operative relation and thereby fixes the cross slide 98 in the desired position. As shown in Figs. 4 and 5, the control pawl 131 has a finger piece 144 by which it may be depressed to disengage the pawl 131 from the ratchet wheel 125, and the pawl 131 also has a tail piece 145 which, in the disengaging movement of pawl 131, engages a roller 146 on the pawl 130 to shift said pawl 130 out of engagement with the ratchet 125 to thereby release the cross slide 98 to the restoring action of the springs 75', Fig. 10. A spring 147 acting between the tail piece 145 and the carriage 75 tends to maintain the control pawl 131 in operative engagement with the ratchet wheel 125.

The requisite step-by-step character-spacing movement of the carriage 75 is effected by means provided to control a spring-biased tendency of the carriage 75 to shift toward the right, as viewed in Fig. 1. Such a spring bias may be imparted to the carriage by a conventional tensioning drum TD, Fig. 1, mounted on the extending right end of the rail 96 and operatively connected to the carriage 75 by a flexible band 150 as shown in Fig. 8.

The means herein provided for controlling the spring-biased right-hand movement of the car-

riage 75 is preferably such as to simplify and cooperate in part in attaining a tabulating control of the carriage as well as affording a back spacing movement and such means include a rack 157 operatively associated with the carriage, a ratchet and pawl mechanism, and a tabulating disc, and a control shaft 170, as fully described in my aforesaid Patent No. 2,265,229.

Character spacing is effected automatically near the end of each embossing operation by suitable means such as that shown and described in Patent No. 1,831,103, patented November 10, 1931.

In order that the operator may manually shift the carriage 75 back and forth, as for the loading and unloading operations, means is provided whereby the carriage may be released from the controlling action of the character spacing escapement. This means preferably includes a manually operable release means located on the carriage 75, and as shown herein, comprises a bell crank lever 220 mounted on a shaft 221, Figs. 9 and 10, within the carriage 75 and having one arm 222 thereof projecting forwardly through an opening 223 in the forward side of the carriage. The arm 222 constitutes a carriage release lever and is positioned directly over a fixed gripping piece 224 so that an operator may conveniently depress the release lever 222. A spring 225 urges the release lever 222 to an elevated position and as shown in Fig. 10, means is provided in association with the rearwardly projecting arm 226 of the bell crank 220 to release the pawl 162 from the ratchet wheel 160 when the release lever 222 is depressed.

This last-mentioned means is preferably operable in any position of the rack 157 and the carriage 75, and as herein shown comprises a horizontally positioned angle bar 230, Figs. 8, 9 and 10, mounted on the rail 96 for transverse or vertical shifting movement by the arm 226, and arranged, when elevated from its position of Fig. 10, to release the escapement pawl 162 and thereby permit free traversing movement of the carriage. To this end the angle bar 230 has a forwardly facing channel portion 231 at its left end, Fig. 8, into which a roller 232, Fig. 10, on the rear face of the pawl 162 projects, and the bar 230 is suspended on parallel links 233 from the rail 96. Thus the bar 230 is maintained in a horizontal position at all times and it is of such a length that the carriage 75 may be shifted a substantial distance to the right, as viewed in Figs. 1 and 8, while still maintaining the roller 234 on the arm 226 beneath the forwardly projecting flange of the bar 230. Hence, when the carriage is located at any point within this range, the release lever 222 may be depressed and the carriage traversed freely back and forth, and upon return of the lever 222 to its normal position the escapement pawl 162 again becomes effective to hold the carriage in its new position.

As shown in Fig. 8, the rack 157 is releasably connected to the carriage 75 by means of the latch member 158 carried by the rack 157, which 65 latch has a notch 240 that is normally maintained in engagement with a lug 241 on the carriage 75 by means of a leaf spring 242 acting upon the latch 158. In some instances it is desirable to move the carriage 75 to the right beyond the range of movement of the rack 157 for the purpose of smoothing the embossed letters by means of a plate roller attachment (not shown). When such rolling of the plate 42 is desired, the carriage 75 is moved to the right, Fig. 8, until a beveled surface 243 on the latch member 158

strikes a pin 244 on the rail 96, so that the latch 158 is disengaged from the tooth 241. The rack 157 then remains in substantially the position of Fig. 8 while the carriage 75 is shifted farther to the right. In the return movement of the carriage the tooth 241 engages the left side of the notch 240 so as to shift the rack 157 to the left, Fig. 8, and to cause re-engagement of the latch 158 with the tooth 241.

It will be apparent from the foregoing description that I have provided an arrangement which materially expedites and simplifies the production of printing plates or the like in embossing machines of the character set forth hereinabove. More specifically, the return of the carriage to its initial position causes the cross slide to be line spaced thereby to speed and facilitate the production of embossed plates by the machine.

While I have illustrated and described a selected embodiment of my invention, it is to be understood that this is capable of variation and modification and I therefore do not wish to be limited to the precise details set forth but desire to avail myself of such changes and alterations as fall within the purview of the following claims.

I claim:

1. In a machine of the character described wherein a work supporting cross slide is mounted on a carriage for line spacing movement, spring means urging said cross slide to a predetermined position and opposing line spacing movement thereof to other line spacing positions, a rack on said cross slide disposed parallel to the path of such line spacing movement, a pinion rotatably mounted on said carriage and meshed with said rack, a ratchet wheel fixed to said pinion for rotation therewith, a control pawl normally engaged with said ratchet to restrain said cross slide against movement by said spring means, an advancing pawl normally engaged with said ratchet and mounted for movement from an initial position to an advanced position to impart a line spacing movement to said cross slide, spring means urging said advancing pawl to said initial position thereof, a line spacing lever shiftably mounted on said carriage and operable when shifted to actuate said advancing pawl to said advanced position, and means for concurrently releasing both of said pawls from said ratchet wheel to enable return of said cross slide to said initial position thereof.

2. In a machine of the character described wherein a work supporting cross slide is mounted on a carriage for line spacing movement, spring means urging said cross slide to a predetermined position and opposing line spacing movement thereof to other line spacing positions, a rack on said cross slide disposed parallel to the path of such line spacing movement, a control shaft mounted in said carriage parallel to the path of movement of said carriage and having a pinion mounted on one end thereof and meshed with said rack, a ratchet wheel fixed on the other end of said shaft, a control pawl disposed adjacent to said other end of said shaft and normally engaged with said ratchet to restrain said cross slide against movement by said spring

means, an advancing pawl normally engaged with said ratchet and mounted for movement from an initial position to an advanced position to impart a line spacing movement to said cross slide, spring means urging said advancing pawl to said initial position thereof, a line spacing lever extending from and shiftably mounted on said carriage and operable when shifted to actuate said advancing pawl to said advanced position, and means for concurrently releasing both of said pawls from said ratchet wheel to enable return of said cross slide to said initial position thereof.

3. In a machine of the character described wherein a work supporting cross slide is mounted on a carriage for line spacing movement, spring means urging said cross slide to a predetermined position and opposing line spacing movement thereof to other line spacing positions, a rack on said cross slide disposed parallel to the path of such line spacing movement, a pinion rotatably mounted on said carriage and meshed with said rack, a ratchet wheel fixed to said pinion for rotation therewith, a control pawl normally engaged with said ratchet to restrain said cross slide against movement by said spring means, an advancing pawl normally engaged with said ratchet and mounted for movement from an initial position to an advanced position to impart a line spacing movement to said cross slide, spring means urging said advancing pawl to said initial position thereof, a line spacing lever mounted on said carriage for shifting movement through an active stroke generally parallel to the path of said carriage and in an active direction opposite to said advancing movements of said carriage, means operable by said line spacing lever in its active stroke to actuate said advancing pawl to thereby impart line spacing movement to said cross slide, means limiting the active stroke of said lever whereby continued actuation of said lever in said active direction imparts return movement to said carriage to said initial position thereof, and means for concurrently releasing said advancing pawl and said control pawl to enable said cross slide to return to said predetermined position.

4. In a machine of the character described wherein a work supporting cross slide is mounted on a carriage for line spacing movement, a rack formed on said cross slide and a pinion on said carriage for advancing said cross slide, spring means acting to retract said cross slide, means for advancing said cross slide or releasing the same for retraction comprising a ratchet wheel fixed to rotate with said pinion, a control pawl normally urged into engagement with said ratchet wheel to prevent retraction of the cross slide and releasable therefrom to permit retraction, an advancing pawl normally urged to engage said ratchet, means for shifting said advancing pawl from an initial position to advance said carriage, means to return said advancing pawl to said initial position, and means operated by said control pawl in its releasing movement to release said advancing pawl from said ratchet wheel.
